HEAD FOR A SHAMPOO DISPENSER-APPLICATOR

David D. Tompkins, Columbus, Ohio, assignor to Bissell Inc., Grand Rapids, Mich., a corporation of Michigan

Filed Sept. 26, 1969, Ser. No. 19,306

Term of patent 14 years

Int. Cl. D4—01, 02

U.S. Cl. D4—7

FIG. 1

FIG. 2

FIG. 3

FIG. 4

FIG. 1 is a side elevation of a head for a shampoo dispenser-applicator, the opposite side being a mirror image thereof;

FIG. 2 is a front elevation of the applicator;

FIG. 3 is a rear elevation thereof; and

FIG. 4 is a top plan view thereof.

I claim:

The ornamental design for a head for a shampoo dispenser-applicator, substantially as shown and described.
